Fred J. Dawson, Bronx, N. Y., assignor to Ortho Products, Inc., Linden, N. J., a corporation of New Jersey

Application March 27, 1943, Serial No. 480,855

3 Claims. (Cl. 206—12)

This invention relates to cabinets of the type particularly suitable for first aid cabinets and the like, although it will be apparent that the invention is not limited to such uses.

In many instances it is desired to have a cabinet such as a first aid kit, a repair kit, a sewing kit, or the like which is and remains complete for some desired service. With such kits it is highly desirable that the entire contents be retained in desired order and yet be completely available and accessible for ready and instant use. It is also desirable in most instances to enforce replacement of any article removed before the kit can be closed, thus not only enforcing replacement in the proper order and arrangement but minimizing the possibility of leaving some of the contents of the kit behind and insuring completeness of the kit at all times.

It has been found convenient to have a multiple compartment kit resembling in general construction a "Gladstone" bag because it provides two independent compartments. Such arrangements, however, have had in the past a decided drawback in that as ordinarily constructed the contents of both compartments are not readily accessible at the same time. Furthermore, it frequently happens that while the combined depth of the two compartments is adequate a division of this depth cannot be made which will satisfactorily receive all of the desired articles in the desired order and arrangement.

It is an object therefore of this invention to provide an improved cabinet, particularly although not necessarily of the "Gladstone" type which has one or more of the foregoing desired advantages without the drawbacks that accompanied such cabinets in the past.

A better understanding of this invention may be had from the following description when taken in connection with the accompanying drawings in which:

Fig. 1 is an isometric view of a cabinet such as a first aid kit embodying the principles of this invention, the cabinet being closed for transporting.

Fig. 2 is an end elevation of the same when fully opened.

Fig. 3 is a plan view of Fig. 2.

Fig. 4 is an enlarged cross section on the line 4—4 of Fig. 3 but with the cabinet closed.

Fig. 5 is a cross section on the line 5—5 of Fig. 3.

Fig. 6 is a vertical fragmentary detail section on the line 6—6 of Fig. 5.

Referring to the drawings, there is illustrated

an improved cabinet particularly suitable as a first aid cabinet which cabinet is of the "Gladstone" type of construction, that is, it is made up of two compartments 1 and 3 hinged together at 5 along one of its longitudinal or longer sides so that the two compartments can be folded together with their interiors facing each other and retained in this closed position by means of customary latches 7. The entire cabinet may conveniently be carried by means of the usual handles 9, one of which is securely fastened to the top of each compartment.

Each compartment is provided with an individual cover. That is, compartment 1 has a cover 11 hinged at 13 to an inturned flange adjacent one of the edges of the compartment other than that edge carrying the hinge 5 and preferably the opposite longitudinal edge. Compartment 3 is provided with a similar cover 15 hinged at 17 to the inturned flange of the longitudinal edge of compartment 3 opposite its hinge 5. It will be understood that if the cabinet is of the suitcase type rather than of the "Gladstone" type, that is, if it is provided with only one compartment, the usual lid would comprise the cover for the compartment or cabinet. Each of the covers 11 and 15 is so hinged and constructed as to lie within the cabinet when the latter is closed and are provided with slide latches 19 for retaining the covers in closed positions. The covers are adapted to open outwardly so as to give complete access to the interiors of the two compartments. For this reason, cover 15 is provided with slots 21 to admit passage of the clasps 1 there-through, thus permitting full opening of the cover 15.

In order to accommodate articles which may have a greater depth than the depth of either compartment but less than the combined depth of the cabinet, cover 15 is offset or provided with a depressed portion 23 (looking at the cover in open position, Fig. 2) which, when the cover and cabinet are closed, will extend into the compartment 1 thus accommodating articles in compartment 3 of greater depth than this compartment. To accommodate this depression, which becomes a raised portion when cover 15 is closed, cover 11 is provided with a complementary or corresponding raised portion 25 (considering the cover open, Fig. 2) which becomes a depressed portion when cover 11 is closed whereby the two portions 23 and 25 will nest into each other when the entire cabinet is closed. The effect of this construction is that when the entire cabinet is closed a portion of compartment 3 will, through

the arrangement of the covers, extend into compartment 1, yet the contents of each compartment will be retained in their respective positions and compartments.

As illustrated, the two compartments 1 and 3 are partitioned off in any suitable manner to accommodate the compartments for the reception of any desired articles. In addition to this, compartment 1 is provided with a series of receptacles or receivers 27 illustrated as bottle receptacles which are hinged at their lower ends at 29 to the bottom of the compartment in such a manner as to permit swinging outwardly, or upwardly if the cabinet is open flatwise on the ground, to permit removal of the bottles, containers, or other articles supported in the receptacles. These receptacles are of greater height when in outward or upright position than the depth of the compartment to which they are pivoted and are provided with means, in the present instance an individual spring 31 (Figs. 5 and 6), which normally urges each receptacle outwardly or upwardly in such a manner as to prevent closing of the lids 11 and 15 and consequently closing of the cabinet until the receptacles are returned to retracted or lowered positions. In this manner, attention of the user of the cabinet is called to any failure on his part to replace any of the articles in the receptacles.

It is preferred that the springs 31 be of sufficient strength only to raise an empty receptacle because otherwise there might be a tendency to throw the bottles violently in upright position. With the springs of sufficient strength to move the empty receptacles only, no danger of unwanted movement of the receptacle and its contents is likely. Furthermore, the receptacles will remain in retracted or lowered position when they contain their proper articles so that closing of lid 11 is not hampered by a tendency of the receptacles to move toward upright position under the influence of the springs.

It will be apparent that by the foregoing invention there is provided a compact cabinet particularly suitable as a first aid cabinet in which the contents are retained in desired order and position, in which the contents are readily accessible, and in which the contents or a portion of them must be replaced before complete closing of the cabinet is possible. In other words, there is an enforcement tending to prevent closing of the cabinet without replacement of all the contents thereof, thus assuring that the cabinet will remain complete as to its contents at all times.

It will also be apparent to those skilled in the art that variations in details of construction may be made without departing from the spirit and scope of the invention as defined in the appended claims. By way of example, only, the spring action of the bottle receptacles may resemble that

generally termed a toggle action, that is, the springs 31 may be so arranged as is common in toggle actions to pass over center positions and urge the receptacles into either extended or retracted positions.

I claim:

1. A cabinet comprising two compartments hingedly connected adjacent one edge and adapted to be folded together into closed position with their interiors facing each other, a cover for each compartment hingedly connected adjacent one edge of each compartment other than said connecting hinged edge whereby the covers will open outwardly away from said compartments to give clear access thereto when open and adapted to lie within and separate the compartments when the covers and compartments are in closed position, one of said covers having a raised portion whereby one compartment in effect extends into the other compartment to accommodate and enclose articles in one compartment having a depth greater than that of the major portion of said compartment.

2. A cabinet comprising two compartments hingedly connected adjacent one edge and adapted to be folded together into closed position with their interiors facing each other, a cover for each compartment hingedly connected adjacent one edge of each compartment other than said connecting hinged edge whereby the covers will open outwardly away from said compartments to give clear access thereto when open and adapted to lie within and separate the compartments when the covers and compartments are in closed position, one of said covers having a raised portion, the other of said covers having a depressed portion said raised and depressed portions being positioned relatively to each other so as to nest together when the cabinet is closed, whereby one compartment in effect extends into the other compartment to accommodate and enclose articles in one compartment having a depth greater than that of the major portion of said compartment.

3. A cabinet comprising a compartment; a cover for said compartment; a receptacle pivoted to said compartment for movement to and from upright position, said receptacle being of greater height than the depth of said compartment when said receptacle is in upright position and capable of being received in said compartment when moved from its upright position and having portions for removably receiving an article; and means normally urging said receptacle about its pivot into upright position whereby when said receptacle is empty and in upright position it will prevent closing said cover without first moving said receptacle about its pivot from its upright position.

FRED J. DAWSON.
